PIPE HANGER

Lloyd F. Bender, Hayward, Wis. 54843

Filed July 27, 1966, Ser. No. 3,225

Term of patent 14 years

(Cl. D54—1)

FIGURE 1 is a perspective view of a pipe hanger embodying my new design;

FIGURE 2 is a top plan view thereof, the bottom being a mirror image of the top shown;

FIGURE 3 is an elevational view taken from one side thereof, the opposite side being the same as the side shown;

FIGURE 4 is a front elevational view thereof; and

FIGURE 5 is a rear elevational view thereof.

I claim:

The ornamental design for a pipe hanger, substantially as shown and described.
